UNITED STATES PATENT OFFICE.

PRINCE L. ROYAL AND JOHN W. OVERBY, OF BUFORD, GEORGIA, ASSIGNEES TO BONA ALLEN, INC., OF BUFORD, GEORGIA, A CORPORATION OF GEORGIA.

SHOE.

Application filed July 27, 1925. Serial No. 46,455.

The present invention relates to shoes, and more particularly to the novel construction of shoe and to a novel intermediate sole for application to the shoe.

5 An object of the present invention is to provide an intermediate sole which may be incorporated in the shoe structure by a through stitch and which simulates the welt and is also constructed to provide a sealing 10 bead or rib for fitting against the outside of the upper where the same is joined to the sole of the shoe.

Another object of the invention is to provide a structure of intermediate sole which 15 is skived and constructed to cover and have incorporated therein as a part of the same a bead or strip to reinforce and hold in raised position a ridge extending about the marginal edge portion of the fore part of the sole 20 to provide a supporting and sealing member as an integral part of the intermediate sole.

Another object of the invention is to provide an intermediate sole with an outer edge 25 structure simulating a welt and which is adapted to be stitched or otherwise suitably secured to the out sole in the manner of a welt and an intermediate sole which while simulating a welt may be secured by 30 through stitching to the in sole and out sole of a shoe with an inturned edge of the upper therebetween.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a fragmentary side elevation of the fore part of a shoe, showing a structure according to the present invention.

Figure 2 is a transverse section taken 45 through the same substantially on the line 2-2 of Figure 1.

Figure 3 is a fragmentary upper face view of the intermediate sole detached and on an enlarged scale.

Figure 4 is a similar view, showing a slight modification in the structure of the intermediate sole, and

Figure 5 is a transverse section taken through the modified form of intermediate sole.

Referring to the drawings 10 designates the upper of a shoe, generally, 11 the in sole and 12 the out sole, all of which are of conventional form.

According to the present invention an intermediate sole 13 is provided which simulates the in sole 11 with the exception that it is of larger dimensions and extends throughout the fore and heel parts of the shoe. The enlargement of the sole 13 is in an edgewise direction, and as shown in Figure 2, provides a welt portion 14 which extends outwardly beyond the upper 10 and is adapted to be secured by a line of stitching 15 or the like to the out sole 12 in the manner of an ordinary welt. The intermediate sole 13 is provided with an upper supporting and sealing bead or ridge 16 formed as an inherent part of the intermediate sole. As shown in Figures 2 and 3, this bead or ridge may be formed by skiving the upper portion of the intermediate sole 13 to separate the skin layer 17 therefrom sufficiently to double up a bead or ridge 16 in suitably spaced relation to the outer marginal edge 80 of the intermediate sole 13. Beneath this ridge or bead 16 is placed a reinforcing and retaining strip 18 of leather or the like which may be cut from the marginal edge of the intermediate sole 13 and which is embedded in the structure of the intermediate sole by being encased within the ridge 16 and secured therein by cement or the like.

In the present instance this skiving or separating of the skin 18 may be accomplished by cutting the intermediate sole from its upper face as shown at 19 and working outwardly toward the edge of the intermediate sole to the desired distance in order to lift the upper layer 17 and pucker or draw the same upwardly into the bead form desired. The strip 18 is now inserted in the upwardly pucker portion of the

layer 17, and the inner free edge of the layer pressed down against the upper side of the intermediate sole 13 and cemented or otherwise suitably affixed thereto. Of course by this construction the upper surface portion of the intermediate sole 13 is recessed or cut away as at 20, but this part is covered up by the in sole 11 as shown in Figure 2.

- 10 As shown in Figures 4 and 5 this upper skin portion 21 of the intermediate sole 13 may be skived or cut from the outer marginal edge of the sole 13 inwardly to the desired point from which the ridge or bead 16 is to be raised. In this case the outer projecting portion of the sole 13, beyond the upper layer 21, may be cut off to provide the reinforcing strip 18. In such case the upper skin portion 21 of the intermediate 15 sole 13 is left uninterrupted within the bead 16 as shown to advantage in Figures 4 and 5.

Intermediate soles of this construction may be manufactured and sold independently of the shoes for incorporation in shoe structures in manufacturing, making repairs and the like. The intermediate sole 13 is merely substituted for the ordinary welt and the inner sole 11, the intermediate sole 13 and the out sole 12 may be secured together by nailing, stitching or the like as shown at 22 in Figure 2, such fastening means 22 also passing through the in-turned edge of the upper 10 so as to secure the upper in its ordinary position between the in sole 11 and the out sole 12. It will be noted that the bead 16 bears against the upper 11 at its juncture with the intermediate sole 13 and holds the upper in place, 20 imparts a neat finish to the product, and at the same time affords a means for sealing the connection between the upper and the sole to exclude moisture and the like.

It is obvious that various changes and 25 modifications may be made in the details

of construction and design of the above specifically described embodiment of this invention without departing from the spirit thereof, such changes and modifications being restricted only by the scope of the following claims.

What is claimed is:—

1. In a shoe, the combination with an upper, an in sole therein, and an out sole therefor, an intermediate sole arranged between the in sole and the out sole and conforming at its outer marginal edge to the outer marginal edge of the out sole and supporting the inturned edge of the upper, said intermediate sole having an upstanding ridge spaced inwardly from its marginal edge and lying against the outer side of the upper to support and seal the same, securing means extending through all of said soles and through the inturned edge of the upper for uniting all of the same together and a line of stitching simulating a welt connection extending through the outer marginal edge portions of the intermediate and out soles.

2. An intermediate sole for shoes comprising a flat body portion skived at its upper surface to separate the surface skin from the body part of the sole, said skin portion being crimped upwardly to provide a bead on the upper face of the sole spaced inwardly from its marginal edge, and a reinforcing strip secured within said bead to stiffen and support the same.

3. An intermediate sole for shoes comprising a body portion skived at its upper surface to separate the surface skin from the body part of the sole, said skin portion being crimped upwardly to provide a bead on the upper face of the sole spaced inwardly from its marginal edge and for fitting against the outer edge portion of the upper.

JOHN W. OVERBY.
PRINCE L. ROYAL.
